UNITED STATES PATENT OFFICE

2,532,193

PROCESS FOR IMPREGNATING WOOD WITH
SODIUM THIOSULFATERaymond G. Ramsey, Driver, Va., assignor to
American Package Corporation, Portsmouth,
Va.

Application July 21, 1947, Serial No. 762,365

1 Claim. (Cl. 117—147)

1

This invention relates to a method of treating wood.

It is an object of this invention to provide an improved method of treating wood for the purpose of eliminating cracking, splitting, and checking, particularly when the wood is bent into shapes suitable for manufacturing containers, which includes placing sodium thiosulphate on the wood, and subjecting the coated wood to heat and pressure.

Another object of this invention is to provide an improved method of treating wood in which the wood is impregnated with sodium thiosulphate. The use of sodium thiosulphate is provided in order that less material need be used and a shorter time required to treat the wood than in the prior method of treating wood with urea.

With the above and other objects in view, my invention consists in the arrangement, combination and details of construction disclosed in the drawings and specification, and then more particularly pointed out in the appended claim.

In the drawings,

Figure 1 is a detail side elevation of wood treating apparatus constructed according to an embodiment of this invention.

Figure 2 is a longitudinal section of the pressure tank with the gauge mounted therein.

Figure 3 is a sectional view taken substantially on the line 3—3 of Figure 2.

Figure 4 is a sectional view taken substantially on the line 4—4 of Figure 2.

Figure 5 is a fragmentary plan view of the telescoping track sections taken substantially on the line 5—5 of Figure 2; and

Figure 6 is a fragmentary vertical section of the front portion of the carriage.

Referring to the drawings, the numeral 10 designates generally a pressure tank formed with a horizontally disposed cylindrical side wall 11, a closed rear end wall 12 and a removable front wall 13. The front wall 13 includes a plurality of circumferentially spaced apart locking lugs 14, which are adapted to be engaged with L-shaped keepers 15 carried by an annular flange 16 which is secured to the front end portions of the side wall 11. The front wall 13 is swingably supported by a pivoted arm structure 17 which is pivotally mounted on a pivot 18 carried by ears 19 extending forwardly from the annulus 16.

The inner end portion of the arm structure 17 includes a bushing which loosely engages about a stud 21 carried by the center of the front wall

2

or cap 13. The pressure tank 10 is supported from a pair of base members 22 which are disposed in spaced apart relation. The pressure tank 10 includes a steam intake pipe 26 and a valve 24 arranged for drawing condensate with valve 25 interposed between the valve 24 and the tank 10 so that condensate may be readily drained from the tank or to prevent damage by freezing. The tank 10 has a steam inlet pipe 26 extending from the top thereof and a pressure gauge 27 is mounted adjacent the inlet pipe 26 in the top portion of the tank 10.

A carriage generally designated as 28, is adapted to be removably mounted in the tank 10. The carriage 28 includes a flat bottom wall 29 and upwardly and inwardly curved side walls 30 and 31. A rear end wall 32 closes the rear end of the carriage 28 whereas the forward end of the carriage 28 is open. The side wall 30 is substantially shorter than the side wall 31, the latter wall extending over the vertical center of the carriage and terminating at its free edge in an upwardly opening trough 33. The upper free edge 34 of the side wall 30 is rolled and is spaced from the trough 33. A connecting bar 35 is welded or otherwise fixedly secured to the forward end portions of the walls 30 and 31, so as to prevent spreading or separating of these walls. The space between the upper edge 34 of the side wall 30 and the downwardly extending free edge of the side wall 31 forms a space 36 which permits the positioning of sodium thiosulphate on the upper layers of the wood. The carriage 28 includes at least two pairs of wheels 37 which are adapted to engage U-shaped track members 38 fixedly secured by brackets or supporting members 39 within the pressure tank 10. The flat bottom wall 29 forms a condensate chamber 40 below the carriage 28 within which condensate may collect and from which the condensate may be drained through opening of the drain valve 25 after the steam valve 26 has been moved to closed position.

The customary track members 38 at their forward ends are formed with outwardly flared guide members 41 which are U-shaped in transverse section and secured, as by welding or the like, to the forward ends of the track members 38 and which extend forwardly therefrom, so as to align a pair of U-shaped track members 42 with the track members 38. The track members 42 are secured to a movable carriage generally designated as 43. The carriage 43 includes a frame 44 having a pair of wheels 45 adjacent one end thereof and also having a caster wheel

46 at the opposite end thereof. A substantially ring shaped member 47 is secured to the forward end of the frame 44 and provides a handle by means of which the carriage 43 may be moved from supply of wood toward the pressure tank 10 and away after treatment to place where material is used and thereby keeping the wood hot by the carriage, which is an essential part of the process. The carriage 43 has secured to the forward end portion of the bottom wall 29 thereof an angle member 48 which is formed with a horizontally disposed forwardly projecting flange 49. The angle member 48 and the flange 49 provide a reinforcing means for the forward end of the bottom wall 29. The carriage 43 has mounted in the tracks or rails 42, stop members 50 which limit the movement of the carriage 28 onto the carriage 43 when the carriage 28 is removed from the pressure tank 10. The rails or tracks 38 also have stop members 51 adjacent the inner ends thereof which are engaged by the innermost pair of wheels 37 so as to limit the inward movement of the carriage 28 into the pressure tank 10.

In the process of treating the wood, the wood is placed in the wood treating carriage 28. The wood, if in strips is laid on the flat bottom 29 in layers which may be uneven, so as to provide spaces between the wood or wooden strips for circulation of heat and for the flowing of the sodium thiosulphate together with the moisture of the wood which flows from the wood in the course of the treatment. After a layer of wood has been placed in the treating carriage 28, sodium thiosulphate is distributed thereover, and then additional layers of wood are placed on top of the sodium thiosulphate. The procedure is continued until substantially the entire area of the treating carriage is filled with layers of wood and alternate layers of sodium thiosulphate with a layer of sodium thiosulphate on the top layer of wood. Some of the layers of wood will be exposed as to their lengthwise edges through the space 36.

Additional sodium thiosulphate is concentrated near the ends of the wooden strips on each layer through the space 36 and also on top of the uppermost layer of the wood. This has the advantage of giving the ends of the wood a stronger sodium thiosulphate treatment where it is generally most desirable as the wood ordinarily is most apt to split near or at the ends. The carriage 43 is moved toward the tank 10 so that the tracks 42 will engage the coupling members or guides 41 in order that the tracks will be held in alignment with the tracks 38. The wood treating carriage which is now filled with wood and which has the sodium thiosulphate on the interior thereof is moved inwardly of the pressure tank 10. The end wall 13 is then closed and locked and steam heat is admitted through pipe 26. The steam is preferably dry steam, and under a pressure of from 60 to 150 pounds per sq. in. but less pressure can be used by giving the wood a longer period of treatment. During this time the temperature ranges from 292 degrees Fahrenheit to approximately 370 degrees Fahrenheit. The wood is subjected to the steam pressure for a period

5 of from 15 to 20 minutes, depending on the pressure of the steam. The heat will cause the sodium thiosulphate to dissolve and as the solution of the crystals is under pressure this solution will be forced into the pores and fibers of the wood so as to impregnate the wood.

10 Following the pressure treatment of the wood, the treating carriage 28 is removed from the pressure tank. The wood is kept hot in the treating carriage 28 by insulating or covering means of any suitable character to retain the heat in the wood until the wood is bent and used. The process hereinbefore described provides a means whereby the wood will more readily bend without checking or cracking and will more readily retain its bent form after it has cooled to normal room temperature.

15 By using sodium thiosulphate in place of urea in the treatment of wood a smaller amount of material, sodium thiosulphate, is used and the same work is done in less time. Only about two thirds as much sodium thiosulphate is needed as urea, and the time required is from 15 to 20 minutes for sodium thiosulphate as compared to 40 to 75 minutes for urea. The length of time required for this treatment cannot be varied by varying the amount of material with which the wood is covered.

20 The exact configuration illustrated is regarded as the optimum, but some of the desirable results inherent in this disclosure may be obtained by various slight modifications including some departure from the exact configuration shown, and it is therefore, requested that the scope of the invention should be regarded as limited only by the terms of the claim.

25 What I claim is:

30 A method of treating wood to prevent splitting and cracking which comprises placing a layer of wood in a receptacle, covering said layer of wood with crystalline sodium thiosulphate, concentrating additional sodium thiosulphate adjacent the ends of the layer, adding a second layer of wood and repeating the process and subjecting the stacked layers of wood and sodium thiosulphate to dry steam between 290° F. and 375° F. at a pressure between 60 and 150 lbs. per sq. in. for a period of time between 15 and 20 minutes.

35 RAYMOND G. RAMSEY.
